R. R. STEIN.

BRAKE.

APPLICATION FILED MAY 14, 1908.

913,781.

Patented Mar. 2, 1909.

UNITED STATES PATENT OFFICE.

ROBERT R. STEIN, OF SEATTLE, WASHINGTON.

BRAKE.

No. 913,781.

Specification of Letters Patent.

Patented March 2, 1909.

Application filed May 14, 1908. Serial No. 432,943.

To all whom it may concern:

Be it known that I, ROBERT R. STEIN, a citizen of the United States of America, and a resident of the city of Seattle, in the county of King and State of Washington, have invented certain new and useful Improvements in Brakes, of which the following is a specification.

My invention has particular reference to 10 a rotary brake.

The primary object of the invention is to provide an improved self applying brake.

A further object is the provision of a 15 brake mechanism of the above type which shall be under control for adjustment or application by auxiliary force to obtain a desired braking effect under varying conditions of speed.

Other objects and advantages will be set 20 forth as the description progresses and the features of novelty on which I desire protection defined in the claims.

In the accompanying drawing I have illustrated my invention in such form as now 25 preferred by me.

With reference to the drawing, wherein like reference numerals designate corresponding parts throughout: Figure 1 is a side view of the invention in partial section 30 showing the same applied to a car. Fig. 2 is a transverse section taken on line 2—2 of Fig. 1, and Figs. 3 and 4 are fragmentary detail views.

In the present embodiment I have illustrated my invention applied directly to an 35 axle 1 having secured thereto a track wheel 2. Mounted on axle 1 are supports, as 3, each comprising a head 4 provided with opposite arms 5 which are swingingly engaged 40 with pivots 6 projecting laterally from axle 1 and secured thereto. Carried by the supports 3 are shoes as 7 each having suitable connection with a respective support for outward movement relatively thereto. In the 45 form of connection shown each shoe 7 is provided with stems 8 which are slidably engaged with adjacent head 4 and provided on their inner end portions with collars 9 having screw threaded connection, each with a 50 respective stem. Lying about the stems 8 are coiled springs 10 which engage the collars 9 and heads 4 to yieldingly hold the shoes 7 from outward movement on the supports.

55 Connected with the supports 3 I have shown a controlling means including a

sleeve 12 slidably mounted on axle 1 and connected with said supports by links as 11. This sleeve is held to rotation with the axle by means of a feather or the like and engaged with a lever 14, fulcrumed at 14', by means of a ring 15 which fits freely in an annular groove of said sleeve and carries suitable pins 16 engaging furcations of said lever. Mounted on lever 14 is a catch 17 conveniently consisting of a flat spring normally engaging at one end with a quadrant 18 and suitably arranged to yield and ride the teeth of said quadrant when pressure is applied to lever 14 to swing the same in either direction. As it may be desired at times to release the controlling mechanism from quadrant 18 I preferably pivot catch 17 on lever 14 so that the catch may be swung to disengaging position relatively to 65 the quadrant as indicated in Fig. 4. Each shoe 7 is preferably formed with angularly disposed bearing surfaces as 7', 7" which are related to braking surfaces 19, 20 respectively, the latter of which extends with 70 the path of the shoes as they swing with supports 3 while the surface 19 extends across said path. These braking surfaces are conveniently provided on a hemispherical casting 21 secured to car body A and having 75 sleeve 12 and axle 1 journaled in the wall thereof. The normal position of the brake shoes and attendant mechanism is indicated diagrammatically by broken lines in Fig. 1.

Upon rotation of axle 1, centrifugal force 80 tends to swing supports 3 outwardly on their pivots and also shift the shoes 7 outwardly on said supports. The catch 17 is however, preferably of suitable resistance to retain the supports in normal position up 85 to a given rate of speed, while the springs 10, primarily placed under suitable tension by adjustment of the collars 9, yield to centrifugal force of the shoes 7 and permit them to engage surface 19 when such speed 90 is reached and thereby obtain a braking effect automatically. Should the effect of the shoes 7 as thus applied fail to prevent further increment of speed, centrifugal force of the shoes and their supports will 95 overcome the resistance of catch 17 and adjust said supports outwardly to carry the shoes in a wider circle of revolution and thereby augment the braking effect. This adjustment of the supports will be continued, under abnormal conditions of speed, 100 until the shoes are finally applied to braking 110

surface 20. If the braking effect thus obtained fails to control the speed a greater resistance may be obtained by applying auxiliary force to lever 14. For example 5 the operator grasps lever 14 and presses the same in the proper direction to force the shoes 7 more firmly against the braking surface 20.

It will be obvious that the controlling 10 mechanism may be operated manually as desired to swing the supports 3 from normal position to apply the shoes 7 to surface 20, or to adjust the said supports, as indicated by bold lines in Fig. 1, to carry the shoes 15 7 in a wider circle of revolution and thereby render the brake more sensitive. If desired to obtain a braking effect automatically at comparatively low speed catch 17 is disengaged from quadrant 18 to release the 20 controlling mechanism for freer action of supports 3 responsively to centrifugal force to carry the brake shoes against braking surface 20.

Having thus described my invention, 25 what I claim as new, and desire to secure by Letters Patent of the United States of America, is:

1. A brake comprising a rotatable element, a support movable therewith and adjustable to various inclinations relatively to the axis of such element, means for yieldingly holding said support as adjusted, a shoe connected with said support for outward movement relatively thereto, and means 35 provided with a braking surface extending to oppose outward movement of the shoe at the various adjustments of said support.

2. A brake comprising a rotatable element, a shoe movable therewith and supported for angular adjustment relatively to the axis of such element and outward movement at such adjustments, said shoe being provided with angularly disposed bearing surfaces, and means provided with a braking surface extending along the path of angular adjustment of the shoe and a second angularly disposed braking surface arranged to oppose outward movement of said shoe.

50 3. A brake comprising a rotatable element, a support connected with said element to swing outwardly therefrom, a shoe movable outwardly on said support, and means provided with a braking surface arranged

to be engaged by said shoe and extending 55 with the path of swing thereof and a second braking surface extending across said path for engagement by said shoe.

4. A brake comprising a rotatable element, a support connected with said element 60 to swing outwardly therefrom, means for controlling the swing of such support, a shoe movable outwardly on said support, and means provided with a braking surface extending with the path of swing of said shoe 65 to coact therewith and a second braking surface for co-action with said shoe extending across said path.

5. A brake comprising a rotatable element, a support connected with said element 70 to swing outwardly therefrom, means to yieldingly retain said support from swinging, a shoe movable outwardly on said support and yieldingly retained from so moving, and means provided with a braking surface for co-action with said shoe extending with the path of swing of said support and a second braking surface for co-action with said shoe extending across said path.

6. A brake comprising a rotatable element, a support swingably connected with said element for angular adjustment relatively to the axis thereof, a controlling means connected with the support to adjust the same, a shoe movable outwardly on said element, and means provided with a braking surface for co-action with said shoe extending with the path of swing of said support and a second braking surface for co-action with said shoe extending across said path. 85 90

7. A brake comprising a rotatable element, a support connected to said element for movement therewith and for swinging outwardly therefrom, means for adjustably holding said support against swinging outwardly from said rotatable element, a shoe supported for outward movement on said support, means yieldingly holding said shoe from outward movement on said support, and means provided with a braking surface 95 100 disposed to be engaged by said shoe during outward swinging of said support.

Signed at Seattle, Washington this 6th day of May 1908.

ROBERT R. STEIN.
